UNITED STATES PATENT OFFICE.

HUGO GERNSBACK, OF NEW YORK, N. Y.

POSTAL CARD.

1,209,425.

Specification of Letters Patent. Patented Dec. 19, 1916.

Application filed June 7, 1913, Serial No. 772,291. Renewed May 15, 1916. Serial No. 97,728.

To all whom it may concern:

Be it known that I, HUGO GERNSBACK, a citizen of the United States, residing at New York, in the county of New York and State 5 of New York, have invented new and useful Improvements in Postal Cards, of which the following is a specification.

My invention relates to new and useful improvements in postal cards, and more particularly to the class known as return postal cards, and has for its object to provide a device of this character, with a protecting flap which can be secured without additional fasteners for protecting the stamp on the 15 reverse side of the postal card.

A further object of the invention is to provide a postal card adapted for use by advertisers which is sent to prospective customers who may send the postal card if the 20 concern's literature is desired, with the name and address of the person desiring said literature, said postal card having a portion projecting from the upper edge, one part of which is removed by the person desiring the 25 literature, the balance being folded over to form a flap, the corners of which are inserted in the body of the postal card, and beneath this flap may be placed a stamp, cash, money order or other object.

30 A still further object of the invention is to provide a return postal card, which will contain the name and address of the person desiring the literature of the original sender as well as the postage for carrying the literature through the mail, so that when said 35 postal card is received by the original sender, it is only necessary to paste the same upon the wrapper of the literature, thereby overcoming the necessity of having to write 40 the address, and preventing mistakes in transcribing, and saving considerable time and expense.

With these ends in view, this invention 45 consists in the details of construction and combination of elements hereinafter set forth, and then specifically designated by the claims.

In order that those skilled in the art to 50 which this invention appertains may understand how to make and use the same, I will describe its construction in detail, referring by numerals to the accompanying drawing

forming a part of this specification, in which—

Figure 1, is a view in elevation of the 55 front side of the postal card, as sent to the prospective customer. Fig. 2, is a similar view of the reverse side of the postal card. Fig. 3, is a similar view of the reverse side, with the extensions folded over. Fig. 4, is 60 a similar view showing a portion of the extension removed to form a flap which is inserted in a slot in the body of the postal card. Fig. 5, is a similar view of the front side of the postal card. Fig. 6, is a view in 65 elevation of the reverse side of the postal card, with the flap removed, and a portion of the body cut away ready for attachment to the wrapper of the literature to be mailed. Fig. 7, is a view in elevation of the 70 reverse side of the postal card, illustrating a modified form of my invention and showing the temporary or protecting flap ready to be folded over. Fig. 8, is a similar view showing the protecting flap folded over and 75 inserted in the slot. Fig. 9, is a view similar to Fig. 7, illustrating another form of my device, and Fig. 10, is a similar view showing the corners of the protecting flap inserted in the slots.

80 In carrying out my invention as here embodied, 2 represents a postal card formed from a suitable sheet of material comprising a body 3, and an extension 4 separated from the body by the transverse perforations 85 5, said extension being divided into two parts by the perforations 6 to produce a removable flap 7, and a temporary flap 8. The front face of the body 2 of the postal card is adapted to contain the address of the 90 person or concern sending out the postal cards, relating to their literature which they have for distribution, while the reverse face is marked to receive the name and address of the recipient or prospective customer 95 desiring the literature of the person or concern sending out the postal cards, and both faces are adapted to have a stamp applied thereto at the places having the stamp "indication". The reverse face of the postal card also has a place for correspondence, in order that the person or concern sending out the postal card may know what literature is desired. The reverse side of the pos-

tal card may also contain directions to the postmaster, not to cancel the stamp on the said reverse side, since it is to be used as postage for the literature or merchandise 5 asked for by the prospective customer.

When the postal card is sent to the prospective customer, it may be dispatched flat as shown in Figs. 1 and 2, or it may be mailed with the extension 4 folded over, as 10 shown in Fig. 3 and is generally sent out with a catalogue, although it may be included with any advertising medium sent to the prospective customer. When the recipient desires to mail the same to the original sender, the removable flap 7 is torn off along the perforated lines 5 and 6, said removable flap having directions thereon to show that it must be removed. After the removable flap 7 has been taken off, the 20 temporary flap 8 is folded over upon the stamp on the reverse face of the postal card, and the inner corner of said flap inserted in the slot 9 in the body of the postal card, to prevent said flap from being accidentally 25 forced back, which would expose the return stamp, and this construction overcomes the necessity of using additional fasteners which are expensive as well as a detriment to the apparatus used by the postal authorities for 30 canceling stamps on mail matter.

One side of the temporary flap 8 may contain directions for the use of the postal card, and the face of said temporary flap which is on the outside when said flap is 35 folded over may contain the word "from," and any other desirable indication marks to show that the address on the reverse side is that of the person using the postal card, it being understood that the front side of 40 the postal card contains the name of the addressee, and a stamp for carrying the postal card to its destination.

From the above it will be seen that the stamp or other object may be placed under 45 the temporary flap 8, and sent to the addressee with the postal card, and said flap will prevent the object from becoming lost or mutilated, and in the case of a stamp will prevent the same from being canceled.

50 When the postal card is received by the addressee, the temporary flap 8 is removed, thereby displaying the uncanceled stamp on the reverse side of the postal card, and if found desirable the portion of the card 55 which contains the correspondence and the directions to the post master, may be cut from the body along the lines 10 and 11 after which the remainder of the body shown in Fig. 6, containing the prospective 60 customer's name and address, and uncanceled stamp may be pasted as a label to the wrapper of the literature desired, permitting said literature to be mailed to the prospective customer.

In Figs. 7 and 8 I have shown a modified 65 form of my invention in which the slot 9 in the body of the postal card produces an inverted V, thereby forming a tongue 12 for engaging the temporary or protecting flap 8 to hold the latter in place when it has been 70 folded over.

The construction of the device illustrated 75 in 9 and 10 is similar to that of my preferred form, except that there are two slots 9 for the reception of the two corners of the protecting flap 8 which will more securely hold said flap in place when folded.

A postal card constructed according to 80 this description saves the person or concern sending out literature several operations on each piece of mail such as writing a person's address and stamping the mail matter.

Of course I do not wish to be limited to the exact details of construction as here shown as these may be varied within the 85 limits of the appended claims without departing from the spirit of my invention.

Having thus fully described my invention, what I claim as new and useful, is—

1. A postal card formed from a single 90 piece of suitable material having transverse perforations to form a body, and an extension, said extension having transverse perforations therein to form two flaps arranged longitudinally of each other, said body having a slot therein to receive one corner of one of the flaps after the other has been taken off, and the remaining flap folded upon the reverse side of the body, the front face of the body containing the address of the original 95 sender and a space for a stamp, the reverse face of the body having a place for the recipient's name and address, a place for correspondence, directions to the postmaster and a space for a postage stamp, the flap to 100 be removed containing directions for removing the same and the other flap containing 105 directions for the use of the postal card, and on the other face suitable indications that the card is from the address 110 upon the reverse side of the body, the last mentioned flap and that portion of the body not containing the recipient's name and address being removable, so that it may be used as a label.

115 2. An article of the class described comprising a body or postal card and an extension, the latter divided into two flaps arranged longitudinally of each other, the body containing the addressee's name and a place 120 for a postage stamp on the obverse face and containing a place for the addressor's name and a stamp upon the reverse face, the extension when folded upon the body obscuring the addressor's name, one of the flaps 125 when the other is detached to be folded over upon the reverse face of the body to protect the stamp upon the reverse face of

the body, the exposed face of said remaining flap containing the legend "from," and means for retaining said remaining flap over the stamp against accidental displacement 5 while the card is passing through the mail to prevent the cancellation of said stamp.

In testimony whereof, I have hereunto

affixed my signature in the presence of two subscribing witnesses.

HUGO GERNNSBACK.
